Filed Aug. 10, 1964, Ser. No. 81,216

Term of patent 14 years

(Cl. D64—11)

FIG. 1.

FIG. 2.

FIG. 1 is a front perspective view of such a calculating machine embodying our new design as seen from the top and one side; and

FIG. 2 is a rear perspective view thereof as seen from the top and said side.

The opposite side not shown is the same in appearance as the side shown.

The essential features of the design reside in the portions shown in solid outline.

We claim:

The ornamental design for a calculating machine, substantially as shown and described.
